UNITED STATES PATENT OFFICE.

LOUIS V. ARONSON, OF NEWARK, NEW JERSEY.

POCKET-LIGHTER.

965,149.

Specification of Letters Patent. Patented July 26, 1910.

Application filed April 29, 1910. Serial No. 558,370.

To all whom it may concern:

Be it known that I, LOUIS V. ARONSON, a citizen of the United States, residing in the city of Newark, in the county of Essex and State of New Jersey, have invented certain new and useful Improvements in Pocket-Lighters, of which the following is a full, clear, and exact description, such as will enable others skilled in the art to which it appertains to make, construct, and use the same, reference being had to the accompanying drawings, and to letters of reference marked thereon, forming a part of this specification.

My invention relates to that class of pocket lighters, wherein, a container is provided with an open end portion; a spark-producing element within said open end portion, a scratching element passing through the open end portion of the container in frictional engagement with the spark-producing element, adjustable means secured to the open end of the container adapted to keep the spark-producing element in engagement with the scratching element, and means exteriorly located on the container for returning the scratching element to its original position after forcing the same through the container and against the spark-producing element.

In carrying out my invention, I make use of the structures illustrated in the accompanying drawings, wherein—

Figure 1 is a front view of my improved device. Fig. 2 is a partial longitudinal section of the structure looking in the direction indicated by the arrow in Fig. 1. Fig. 3 is a modified form of my improved structure; and Fig. 4 is a plan view of the structure illustrated in Fig. 1.

Similar letters of reference refer to like parts throughout the specification and drawings.

In the drawings referred to, *a* represents the body or container of the lighter, which consists preferably of a tubular piece of metal, such as brass, steel or other suitable material, in the open end of which is secured the spark-producing element *c*. One form of such spark producing element or spark producing metal alloy consists preferably of cerium and iron. As a convenient means for keeping the spark-producing element *c* in contact with the scratching element *d*, as the same shall be consumed, I have located in the open end of the con-

tainer, a spiral spring *e*, which is acted upon by the knurled cap *b*, which has screw-threaded engagement with the exterior of the open end of the container *a*.

The scratching element *d* is preferably made from a steel rod or bar rectangular in cross-section, and is designed to fit openings of corresponding cross-section, which are formed in the body or container of the lighter, as indicated at *d*³, and is provided upon its upper face with a suitable number of serrations or saw teeth as at *f*, whereby a scratching member or element is produced.

j represents a flat spring, the upper end of which is loosely connected in any convenient manner to the scratching element, preferably by providing said element with a reduced portion as at *d*¹ which is fitted into a slot *d*² formed in the free end of the spring *j*. The lower end of the spring is secured in any convenient manner, as by rivets *l* or otherwise, to the lower end of the container *a*.

Pressing the flat spring *j*, illustrated in Fig. 1, in the direction indicated by the arrow, the scratching element *d* which is loosely connected to said spring, is caused to travel through the openings *d*³ formed in the upper end of the container and the serrated upper face of the scratching element is caused to rub against the under side of the spark-producing element, which is held in frictional engagement with the upper face of the scratching element by means of the spiral spring *e* and cap *b*, thereby causing a shower of sparks to be emitted from the lighter, as indicated at *g*.

In the modified form illustrated in Fig. 3, the scratching element *d* is provided at one end with a knurled head *h*. Interposed between the knurled head *h* and a suitable boss *k* located on one side of the container *a*, and surrounding the scratching element *d*, is a spiral spring *i*, which when depressed by forcing the knurled head toward the container *a*, causes the scratching element to rub against the spark-producing element, thereby emitting a shower of sparks, as indicated at *g*. A pin *m* is secured in the under side of the scratching element to limit the return movement of the same.

The present invention provides a very efficient and exceedingly simple pocket lighter, the same being constructed of a minimum number of parts and reduced to the simplest operative efficiency.

I am aware that changes may be made in the several arrangements of the various parts, as well as in the details of construction thereof, without departing from the scope of my present invention, hence I do not wish to be limited to the exact arrangements and combinations of the parts as herein shown and described, as obvious modifications will suggest themselves to those skilled in the art.

I claim:

1. A pocket lighter comprising a container, said container being formed with an open end portion, a spark-producing element located within said open end portion, means adjustably disposed upon said open end portion of the container for pressing against said spark-producing element, and a scratching element passing transversely through the open end of said container, said scratching element being provided with saw tooth serrations adapted to contact with the spark-producing element.
2. A pocket lighter comprising a container, said container being formed with an open end portion, a spark-producing element adjustably located within said open end portion, a scratching element passing transversely through the open end of said container, said scratching element being provided with saw tooth serrations adapted to contact with the spark-producing element and means connected with said scratching element for operating the same.

3. A pocket lighter comprising a container, said container being formed with an open end portion, a spark-producing element located within said open end portion, means adjustably disposed upon said open end portion of the container for pressing against said spark-producing element, a scratching element passing transversely through the open end of said container, said scratching element being provided with saw tooth serrations adapted to contact with the spark-producing element and means connected with said scratching element for operating the same.

4. A pocket lighter comprising a container, said container being formed with an open end portion, a spark-producing element located within said open end portion, a cap adjustably disposed upon said open end portion of the container, a spring located within said cap and open end portion of said container bearing upon the spark-producing element, a scratching element passing through said container, said scratching element being provided with saw tooth serrations adapted to contact with the spark-producing element and means connected with said scratching element for operating the same.

This specification signed and witnessed this 16th day of April, 1910.

LOUIS V. ARONSON.
